UNITED STATES PATENT OFFICE.

LAMARTINE C. TRENT, OF SALT LAKE CITY, UTAH TERRITORY, ASSIGNOR OF TWO-THIRDS TO WILLIAM J. CHALMERS AND CHARLES S. LEEDS, OF CHICAGO, ILLINOIS.

STONE-CUTTER.

SPECIFICATION forming part of Letters Patent No. 498,995, dated June 6, 1893.

Application filed December 27, 1892, Serial No. 456,428. (No model.)

To all whom it may concern:

Be it known that I, LAMARTINE C. TRENT, of Salt Lake City, Utah Territory, have invented a new and useful Improvement in 5 Stone-Cutters, of which the following is a specification.

The object of my invention is to make a simple, economical and efficient stone cutter for use in scabbling, dressing or gadding stone 10 in quarries; and the invention consists in the features and combinations hereinafter described and claimed.

In the accompanying drawings, Figure 1 is a side elevation of my improved stone cutter 15 as intended for ordinary use; and Fig. 2 a view of a counterbalance for supporting the cutter.

A is a jib crane supporting my improved stone cutter; B a traveler or trolley thereon; 20 C falls suspended from the traveler; D the cutter proper, d the cylinder thereof, d' a piston rod working in the cylinder, d² the cutting tool, d³ handles for guiding the cutter in its work, and d⁴ a pipe for admitting steam or 25 compressed air to the cylinder; E a weight or jacket surrounding the cutter, and e trunnions on opposite sides thereof; F a strap or bail for supporting the cutter; and H a counterbalance for holding the cutter in different 30 positions.

In the methods now usually employed in large stone quarries, the blocks of stone are scabbled into more or less regular shape for 35 shipment; and, after delivery, they are dressed to their desired size and thus made ready for use. This scabbling is performed by hand, which necessarily makes it slow and expensive.

The object of my invention is to provide for 40 the scabbling and dressing of stone by machinery.

My improved stone cutter consists essentially of a weighted cutter, suspended in such manner that it can be easily moved and held 45 in different positions as desired.

In making my improved stone cutter, I erect a jib crane in any suitable position at the quarry, so that large blocks of stone taken out can be placed at any desirable point there-

under. The cutter, which is suspended from 50 the crane, is adapted to be raised by falls or counterbalance to any desired height, and to be oscillated on trunnions at any angle necessary for operation on the stone surface. The cutter is preferably suspended from a 55 trolley or traveler, so that it can be moved back and forth and adapted to operate on any portion of the stone, or in a mine, as desired. It is thus made a very efficient tool, especially 60 adapted for use in mines and quarries, where any number of inconceivable positions are oftentimes required.

The cutter proper is preferably surrounded by a weighted jacket to receive and neutralize the impact, and thus make it possible for 65 the operator to hold the cutter in position, notwithstanding the force of the blow. I prefer to make this weighted jacket separate from the cutter, so as to permit the cutter to be readily removed therefrom for repairs, or for 70 the insertion of new ones. So far as regards this weighted jacket, the cutter is directly the opposite of all similar devices with which I am acquainted, the same being generally made as light as possible, and securely fastened. 75

The cutter, being capable of being swung or moved around at will, may be held in different positions by the operator. In this respect it also differs from all similar constructions with which I am acquainted, the same being 80 rigid or mechanically held in fixed position when in use.

It will of course be understood that I do not intend to limit myself to minor features or details of construction, or to the use of my invention in stone work merely, the same being capable of use for other purposes. On the contrary, I intend to vary form and construction, to omit parts or use equivalents, and to use my invention for other purposes, as circumstances may suggest or render expedient. 85 90

I claim—

1. In combination with a support, a cutter surrounded by a weighted jacket and suspended in trunnions, whereby it may be moved 95 and held in different positions, substantially as described.

2. The combination of a power operating

cutter, and a weighted jacket surrounding the cutter to neutralize the impact in cutting, substantially as described.

3. In combination with a power operating cutter, a weighted jacket surrounding the same to neutralize the impact of the cutting, and means for suspending the cutter in an adjustable manner, substantially as described.

4. The combination of a power operating cutter, a weighted jacket surrounding the same to neutralize the impact of the cutting, means for suspending the cutter in an adjustable manner, means for moving it radi-

ally, and means for moving it laterally, substantially as described.

5. The combination of a power operating cutter, a weighted jacket surrounding the cutter to neutralize the impact of the cutting, a counter balance holding the stone cutter in suspension in an adjustable manner, a traveler for moving it radially, and a crane for moving it laterally, substantially as described.

LAMARTINE C. TRENT.
